UNITED STATES PATENT OFFICE.

EDWY E. WOLBERT, OF CONCRETE, WASHINGTON.

GATE.

Application filed June 29, 1926. Serial No. 119,367.

This invention relates to an improved gate construction for public driveways, farm entrances, and similar places.

The invention has more specific reference 5 to the type of gate which is provided with means located at points at a distance from the gate which serve to permit the gate to be opened or closed without requiring the driver of the vehicle to alight, release the 10 latch and manually push or swing the gate open.

Briefly, the present invention has reference to a gate structure, including a support upon which a pair of curved tracks are pivotally mounted, these tracks supporting a 15 pair of gate sections through the medium of roller carrier disks, the inner ends of the tracks being connected together and normally located in a plane which causes the 20 gate sections to roll by gravity to closing position. Means is provided, however, for moving the inner connected ends of the tracks to a position for causing the gates to roll outwardly and away from each other 25 under the influence of gravity, whereby to permit them to assume an open position. The operating means for the tracks is manually manipulated on opposite sides of the 30 gate structure without requiring the driver of a vehicle to alight and open the gate in the customary manner.

My principal aim is to generally improve upon structures of this class by providing one of comparative simplicity and durability, wherein the parts are novel, are associated in a novel manner, and such as to produce a structurally and patentably different device from similar structures with which I am familiar.

40 In the drawings:

Figure 1 is a view looking at one side of the complete structure, showing the gates closed.

Figure 2 is an end elevation of the same.

45 Referring to the drawings in detail, it will be seen that the main supporting structure is designated generally by the reference character 1. There is a pair of vertical standards 2, having brackets 3 at their upper ends. These standards are connected with a central arch 4, which in turn is connected through the medium of braces 5, with a horizontal cross piece 6. Supported on the 50 crest of the arch is a substantially U-shaped member 7 which functions as a guide in the

manner to be hereinafter made clear. In turn, another U-shaped member 8 is carried by the first named member 7.

Connected, as at 9, to the brackets 3 are longitudinally bowed tracks 10, having 60 curved extremities 11. The inner ends of these tracks are connected to a pair of relatively short links 12. The gate sections are presented by the reference characters 13 and 14. The upper portions of the gates are connected with a pair of rockably mounted carriers 15, which in turn are provided with rollers 16 mounted upon the tracks. As shown in Figure 2, the rollers are of the grooved type, to aid in maintenance upon 70 the tracks and the carriers 15 are of U-shaped form and the free ends of the arms are arched over the peripheral portions of the rollers to provide retainers of the type shown in Figure 2. The gate section 14 is 75 provided at its bottom with a keeper 17, which serves to maintain the two sections in proper alignment and to facilitate their closing in such alignment. It is obvious with this arrangement, that by lifting up on 80 the rear end portions of the tracks the outer end portions will swing downwardly, thus allowing the carriers 15, and the gate sections to roll, by gravity, outwardly away from each other to open position. As before 85 stated, novel, manually operated means are provided for operating the tracks in this manner. The means, are better shown in Figure 2, wherein it will be seen that levers 18 and 19 are provided, these being pivotally 90 connected at their upper ends to a supporting member, which includes a pair of horizontal arms 20 and 21. The arm 20 is connected to a vertical part 22, which is in turn connected to the U-shaped member 8 at its 95 top, as illustrated in Figure 2. The arm 21 is also connected with this part 22, but is provided with a U-shaped portion 23 to accommodate the rocking action of the tracks.

Connected to the intermediate portions of the levers 18 and 19, are wire rods or links 24, which are connected at their upper ends, with a vertical arm 25, riveted on the arch of a rocker member 26. At this time, it will be seen that the rocker is pivotally connected at 27 to an upright 28 on the supporting frame structure 1, the pivotal connections being between the center and one end. A link 29 is connected with the lower bar of this rocker 26 and is also connected at its 110

lower end as shown better in Figure 1, with the intermediate portions of the aforesaid links 12. This constitutes the connection between the rocker and the tracks. The upper 5 end of this link 29 extends upwardly through the U-shaped guide 7, as shown in Figure 2, this preventing side wobbling of the rocker member. To add to its rigidity in construction, I prefer to employ braces 10 30 which are connected at their upper ends to the U-shaped member 8 and at their outer lower ends to the horizontal supporting arms 20 and 21.

In practice, the operating levers 18 are 15 disposed at suitable distances away from the gate sections so that the driver of the vehicle in approaching the gate may simply drive up alongside of one of the depending levers, catch hold of it, and lift it upwardly 20 as represented in Figure 2. Assuming that the driver is approaching the left hand side of the structure as shown in Figure 2, and that he has lifted the lever 19 to the position shown, it is obvious that this will 25 exert a longitudinal thrust upon the rod 24 and in so doing, it will, through the medium of the connection 25, swing the rocker 26 to position. By thus manipulating the parts 19 and 24, the rocker 26 will be moved to 30 position just opposite to that shown in Figure 2, and in so doing, it will lift upwardly upon the link 29 and will in turn lift upwardly upon the pivotal connection between the inner ends of the two tracks 10. As 35 suming, for instance, that the gate sections are in closed position, it is obvious that this will move the tracks to such a position as to permit the gates to roll, by gravity, away from each other to open position. After 40 passing through the gate opening and reaching the lever 18 on the opposite side of the gate structure, the lever will be operated as shown in Figure 2, will relock the rocker 26 to a reverse position as here shown, and 45 will swing the inner pivotally connected ends of the two tracks downwardly, thus permitting the two gate sections to roll by gravity back to closed position. It will thus be seen that the gates are open from one 50 side and closed from the other side. The gates are self adjusting and self aligning.

It is believed that by considering the description in connection with the drawings, a clear comprehension of the construction, 55 arrangement of parts, and operation will be had. Therefore, a more lengthy description is thought unnecessary.

Minor changes coming within the field of invention claimed may be resorted to if desired.

I claim:

1. In a gate structure of the class described, a support, a pair of longitudinally bowed tracks pivotally mounted upon said support, links connecting the inner ends of

the tracks together, a pair of gate sections, hangers pivotally connected to said gate sections, rollers carried by said hangers and mounted upon said tracks, a rocker mounted upon said supporting structure, a connection between said rocker and the inner end portions of the tracks for raising and lowering said inner end portions, a pair of operating levers, supporting means for said levers, and connections between said levers and said rocker.

2. In a gate structure of the class described, a support embodying a pair of vertical uprights, a pair of longitudinally bowed tracks pivotally mounted at their centers upon the upper ends of said uprights, the outer ends of said tracks terminating in hooks, links connecting the inner ends of the tracks together for simultaneous operation, a pair of gate sections disposed between said uprights, and adapted to cooperate in forming a closure, a pair of substantially U-shaped hangers, the bight portions of said hangers being pivotally connected to the upper end portions of said gates, the free end portions of the arms of said hangers being bent upon themselves to provide roller carriers, rollers mounted for rotation in said carriers adapted to roll upon said tracks, and manually manipulated means adapted for moving the inner end portions of said tracks upwardly, to cause the gates to gravitate outwardly to open position.

3. In a gate structure of the class described, a support including a pair of vertical uprights, an arch connecting said uprights together, a horizontal cross piece between the upper end portions of said uprights, braces between said cross piece and said arch, a pair of horizontal supporting arms extending at right angles from said supporting structure, tracks pivotally mounted upon said supporting structure, roller supported gate sections mounted for movement upon said tracks, a frame-like rocker pivotally mounted upon said supporting structure and disposed at right angles thereto, a pair of operating levers pivotally connected to the outer end of said supporting arms and depending therefrom, and connecting links between said levers and said rocker, said rocker having operating connection with said tracks.

4. In a gate structure of the class described, a supporting structure embodying a pair of vertical uprights, an arch connecting the upper ends of the uprights together, a cross piece disposed between said uprights and connected thereto, braces connecting said cross piece with said arch, a pair of gate sections located in alignment with each other between said uprights, hangers pivotally connected to the gates, rollers carried by said hangers, tracks pivotally mounted upon said uprights, said rollers being movable

along said tracks, links connecting the inner ends of the tracks together, a right angularly disposed pivotally mounted frame-like rocker, an upstanding arm carried by said 5 rocker, a pair of supporting arms extending outwardly from the central portion of the supporting structure, levers pivotally con-

nected to the outer ends of said supporting arms, connections between said upright arms and levers, and an operating connection between the rocker and said links. ¹⁰

In testimony whereof I affix my signature.

EDWY E. WOLBERT.
